UNITED STATES PATENT OFFICE

CHARLES F. SMITH, OF BRIDGEPORT, CONNECTICUT, ASSIGNOR TO HOWLAND BAG AND PAPER COMPANY, OF DEXTER, NEW YORK, A CORPORATION OF NEW YORK.

CUTTING MECHANISM.

1,071,473.

Specification of Letters Patent.

Patented Aug. 26, 1913.

Application filed January 3, 1912. Serial No. 669,216.

To all whom it may concern:

Be it known that I, CHARLES F. SMITH, a citizen of the United States, and a resident of Bridgeport, in the county of Fairfield and State of Connecticut, have invented certain new and useful Improvements in Cutting Mechanism, of which the following is a specification.

This invention relates to cutting mechanism, and particularly to mechanism of that class adapted for severing tubular webs into blanks of predetermined length, such as may be suitable for afterward forming into paper bags.

15 The object of my improvements is to provide a mechanism of the class specified, of simple construction, and which may be adjustable for different lengths of blanks.

To these ends my improvements comprise 20 parts and combinations of parts set forth herein and illustrated in their preferred form in the drawings accompanying this specification.

Figure 1 is a side elevation, looking in 25 the direction of arrow 1, Fig. 3, of a cutting mechanism embodying my improvements. Fig. 2 is a fragmentary side elevation looking in the direction of arrow 2, Fig. 3. Fig. 3 is a vertical section on line 3, 3, Fig. 1, 30 looking in the direction of arrow 5. Fig. 4 is a fragmentary cross section on line 4, 4, Fig. 3, showing the cutting members of my improved mechanism in operative coaction. Fig. 5 is a similar view to that of Fig. 4, 35 but showing said cutting members in their return strokes. Fig. 6 is a plan view looking in the direction of arrow 6, Fig. 5, when the cutting members are in approximately the same vertical plane. Fig. 7 is a 40 fragmentary end view to an enlarged scale looking in the direction of arrow 7, Fig. 4. Fig. 8 is a fragmentary end view on an enlarged scale, looking in the direction of arrow 8, Fig. 5. Fig. 9 is a fragmentary 45 plan view of a portion of what is shown in Figs. 7 and 8 and to the same scale as those figures. Fig. 10 is a diagrammatic view of the path of one of the cutters relatively to the float. Figs. 11 and 12 are modified 50 forms of the path shown in Fig. 10. Fig. 13 is a fragmentary sectional elevation of a modification of the crank mechanism parts as shown in Fig. 3. Figs. 14 and 15 are respectively a sectional elevation and an end

elevation of portions of what is shown in 55 Figs. 3 and 2 respectively.

My improved mechanism is conveniently mounted in side frames 9, 10, provided with the usual bearings as 11, for the several shafts. Main shaft 12 has pulley 13 on the 60 outboard right hand end, Fig. 3. Said pulley is omitted from the showing of Fig. 1, in the interest of clarity. Change gear 14 is mounted on said main shaft 12 between pulley 13 and bearing 15 of frame 10. Said 65 gear and pulley are connected for rotation with shaft 12 by key 16. Revolubly mounted on shiftable stud 17 in swinging arm 18, pivotally mounted on extension 19 of bearing 15, first intermediate gear 20 is driven 70 by gear 14 and in turn drives second intermediate gear 21. Said gear 21 is rotatably mounted on stud 22 fixed in frame 10, and drives lower feed roll gears 23 and 25 fixed to shafts 29, 31, respectively. Said lower 75 feed roll gears drive upper feed roll gears 24 and 26, fixed to shafts 30, 32, all respectively. Swinging arm 18 may be held in adjusted position by means of clamp-bolt 27 passing through slot 28 of said arm and engaging frame 10 in the well known manner. Feed rolls 33, 34 fixed to shafts 29, 30 respectively and feed rolls 35, 36 fixed to 80 shafts 31, 32 respectively are efficient for supporting float 37 and for advancing a 85 continuous tubular web thereover in the direction of arrow 5 in the usual manner, well known in the art.

Cutter shafts 39, 40 are mounted for oscillation in opposite sleeves, as 41, 42 for 90 shafts 39 and 43, 44 for shaft 40. Lower cutter shaft sleeves 43, 44 have gears 45, 46 fixed thereto respectively and are driven in unison in clockwise direction (Fig. 1) by gears 47, 48 respectively fixed to main 95 shaft 12 (Fig. 3). Upper sleeves 41, 42 have gears 49, 50 fixed to the inner ends thereof above and in mesh with gears 45, 46, all respectively. Said sleeves 41, 42 are thus driven in anti-clockwise direction (Fig. 100 1). Sleeves 41, 42 and 43, 44 are eccentrically bored, thereby causing shafts 39, 40 to move bodily through eccentric paths. Said sleeves are set relatively to one another to cause said shafts to approach one another 105 simultaneously and then simultaneously retreat from one another, thus giving a to-and-fro movement to cutters 51, 52 mount-

ed on cutter heads 53, 54 on shafts 39, 40, all respectively.

Float 37 is provided with a plurality of regularly spaced slots 55 therethrough whereby a plurality of regularly spaced bars 56 are provided for engagement with correspondingly spaced teeth 57 on cutters 51, 52. Said teeth thus form serrated cutting edges on said cutters, as well known in the art. 10 If desired, bars 56 may be chamfered on their corners as at 58, 59 into more or less close conformity with the profile of the engaging cutters respectively. I also preferably curve said cutters 51, 52 in opposite directions, setting shaft 39 of upper cutter 51 slightly forwardly, in the direction of travel of the web to be cut, of lower shaft 40, so that the pressure of cutting will be equalized on opposite sides of float 37. Cutters 15 51, 52 are timed relatively to each other so that the edge points of severance respectively of the tubular web coincide top and bottom. Also said opposite curving of said cutters is efficient to sever the tubular web 20 with the one ply longer at the middle than the other, thus producing a lip, as well known in the art. I have also found that increased efficiency and simplicity of action 25 may be had by terminating float 37 at approximately the common plane of shafts 39; 40, whereby as soon as the tubular blank is severed, it is freed from said float.

For oscillating cutter shafts 39, 40 for causing cutters 51, 52 thereon to coact in the 30 forward portion of their oscillation with float 37 during their movement toward each other, I employ the following means: Segment gear 61 is mounted for free rotation on the outboard end of sleeve 41, and is engaged and driven by segment gear 62 similarly mounted on sleeve 43. Lower segment gear 62 is provided with a downwardly reaching slotted arm 63 in slot 64 of which block 65 is slidably mounted. Said block is 35 pivotally mounted on crank pin 66 of crank disk 67 fixed to the adjacent outboard end of main shaft 12. Said crank pin 66 is slidably mounted in slot 68 of said crank disk 67 and may be adjusted radially thereof by 40 means of screw 69, as well known in the general art. Thus the revolution of disk 67 will cause segment gears 61, 62 to oscillate in unison. For communicating that oscillation to eccentrically mounted shafts 39, 40, I fix 45 to the adjacent outboard ends thereof, slotted heads, 69, 70 respectively. In slots 71, 72 thereof I mount sliding blocks 73, 74 and which blocks in turn are pivotally mounted on pins 75, 76 fixed in segment gears 61, 62, 50 all respectively. In Fig. 10 broken line 77 shows the path of teeth 57 of cutter 52 when crank pin 66 is located relatively to shaft 12 as shown in Fig. 3, and broken line 78, Fig. 11, shows the path of said teeth 57 when 55 crank pin 66 is moved inwardly toward

shaft 12 as far as may be, in the form of arrangement shown in Fig. 3.

In the modification of Fig. 13 I have arranged disk 67 to permit crank pin 66 to be moved into coaxial relation with shaft 12 70 as shown, whereby no oscillation of arms 63 and segment gears 61, 62 will be had.

In the modification of Figs. 14 and 15 I have moved pivoted blocks 73, 74 toward the axes of their shafts 39, 40 respectively, so 75 as to increase the stroke of cutters 51, 52 relatively to float 37. With the modified arrangement of Figs. 13, 14 and 15, the coaction of cutters 51, 52 with float 37 will be had only by means of the eccentrically orbital movements of shafts 39, 40, said shafts being held against rotation by slotted heads 69, 70, which will slide up and down on blocks 73, 74 and said blocks will oscillate on pins 75, 76. The path of teeth 57 of 80 lower cutter 52 will then conform to broken line 79 of Fig. 12.

It is obvious that upper cutter 51 will have paths of travel relatively to the upper face of float 37 oppositely similar to the paths 90 of lower cutter 52 shown in Figs. 10, 11 and 12 respectively.

I claim:

1. Cutting mechanism including in combination, a float, terminating in a plurality 95 of bars lengthwise said float, a pair of oppositely disposed cutters having serrated edges for coaction top and bottom respectively with the bars of said float, said cutters mounted on opposite shafts respectively, 100 and means for moving said cutters for coaction with said float, said float bars terminating substantially at the common plane of said cutter shafts.

2. Cutting mechanism including in combination, a float, terminating in a plurality of bars lengthwise said float, a pair of oppositely disposed cutters having serrated edges for coaction top and bottom respectively with the bars of said float, said cutters 110 mounted for oscillation on opposite shafts respectively, means for moving said shafts toward and from each other and means for oscillating said shafts, said float bars terminating substantially at the common plane of 115 said cutter shafts.

3. Cutting mechanism including in combination, a float, a pair of oppositely disposed cutters for coaction with opposite sides respectively of said float, means for 120 advancing a tubular web about said float and between said cutters, means for oscillating said cutters, and means for moving said cutters toward and from said float.

4. Cutting mechanism including in combination, a float, a pair of oppositely disposed cutters for coaction with opposite sides respectively of said float, means for 125 advancing a tubular web about said float and between said cutters, means for oscillating 130

- ing said cutters, means for moving said cutters toward and from said float, and means for changing the speed of the cutters relatively to the speed of the web.

5 5. Cutting mechanism including in combination, a float, a pair of oppositely disposed cutters for coaction with opposite sides respectively of said float, means for advancing a tubular web about said float and between said cutters, means for oscillating said cutters, means for moving said cutters toward and from said float, and means for changing the speed of advance of the web.

10 15. 6. Cutting mechanism including in combination, a float, a pair of oppositely disposed cutters for coaction with opposite sides respectively of said float, means for advancing a tubular web about said float and between said cutters, means for oscillating said cutters, means for moving said cutters toward and from said float, means for changing the speed of advance of the web, and means for changing the speed of the web.

20 25. 7. Cutting mechanism including in combination, a float, a pair of oppositely disposed cutters for coaction with opposite sides respectively of said float, means for advancing a tubular web about said float and between said cutters, means for oscillating said cutters, means for moving said cutters toward and from said float, and means for changing the length of stroke of said cutters in coaction with said float.

30 35. 8. Cutting mechanism including in combination, a float, a pair of oppositely disposed cutters for coaction with opposite sides respectively of said float, said cutters mounted on opposite shafts respectively, means for moving said shafts toward and from each other, and means for oscillating said shafts.

40 45. 9. Cutting mechanism including in combination, a float, a pair of oppositely disposed cutters for coaction with opposite sides respectively of said float, said cutters mounted on opposite shafts respectively, means for moving said shafts toward and from each other, means for oscillating said shafts, comprising a slotted arm fixed to one of said shafts, and a revolving crank pin for engagement with the slotted arm.

50 55. 10. Cutting mechanism including in combination, a float, a pair of oppositely disposed cutters for coaction with opposite sides respectively of said float, said cutters mounted for oscillation on opposite shafts respectively, means for moving said shafts toward and from each other, means for oscillating said shafts comprising a slotted arm fixed to one of said shafts, a revolving crank pin for engagement with the slotted arm, and means for changing the stroke of said crank pin.

respectively, means for moving said shafts toward and from each other, means for oscillating said shafts comprising a slotted arm fixed to one of said shafts, a revolving crank pin for engagement with the slotted arm, and means for changing the stroke of said crank pin.

11. Cutting mechanism including in combination, a float, a pair of oppositely disposed cutters for coaction with opposite sides respectively of said float, said cutters mounted on opposite shafts respectively, and means for moving said shafts in eccentric orbits.

12. Cutting mechanism including in combination, a float, a pair of oppositely disposed cutters having serrated edges for co-action top and bottom respectively with said float, said float having its terminal portions shaped for co-action with the serrated edges of said cutters, said cutters being mounted on opposite shafts respectively and means for moving said cutters for co-action with said float, said float terminating substantially at the common plane of said cutter shafts.

13. Cutting mechanism including in combination, a float, a pair of oppositely disposed cutters having serrated edges for co-action top and bottom respectively with said float, said float having its terminal portions shaped for co-action with the serrated edges of said cutters, said cutters being mounted for oscillation on opposite shafts respectively, means for moving said shafts toward and from each other and means for oscillating said shafts, said float terminating substantially at the common plane of said cutter shafts.

14. Cutting mechanism including in combination, a float, a pair of oppositely disposed cutters for co-action with opposite sides respectively of said float, means for advancing a tubular web about said float and between said cutters, means for oscillating said cutters, means for moving said cutters toward and from said float, means for changing the speed of the cutters relatively to the speed of the web and means for changing the length of stroke of said cutters in co-action with said float.
